(57) **CLAIM**

The ornamental design for a tile, as shown and described.

DESCRIPTION

FIG. 1 is a front perspective of a tile showing my new design; FIG. 2 is an enlarged fragmented front perspective view shown in FIG. 1;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is an enlarged fragmented top plan view shown in FIG. 7; and,

FIG. 9 is a bottom plan view thereof.

The broken lines shown in the drawing indicate areas that have been enlarged to show detail of the pattern.
